UNITED STATES PATENT OFFICE.

GRANT G. BERRY, OF BESSEMER, ALABAMA.

CORE FOR CASTING IRON PIPES AND MEANS FOR PRODUCING THE SAME.

Application filed April 13, 1921. Serial No. 461,077.

To all whom it may concern:

Be it known that I, GRANT G. BERRY, a citizen of the United States, residing at Bessemer, in the county of Jefferson, State 5 of Alabama, have invented certain new and useful Improvements in Cores for Casting Iron Pipes and Means for Producing the Same; and I do hereby declare the following to be a full, clear, and exact description of the invention, such as will enable others skilled in the art to which it appertains to make and use the same.

The object of the invention is to provide an improved core for use in the manufacture of cast iron pipes and adapted for arrangement in the mold into which the molten metal is poured, and a method of and machine for producing said core which, by reason of the characteristics of the object 20 to be molded must be adapted to yield diametrically to permit of the contraction of the molten metal as the temperature thereof is reduced in the setting and cooling operation in order to avoid fractures in the completed product; and more especially to provide a casting core and method of and means for producing the same whereby the operation of preparing the same may be accomplished mechanically and under conditions 25 serving to minimize the expenditure of time and labor while effecting a core of increased regularity and uniformity as a means of producing a pipe of uniform interior contour.

In the ordinary recognized practice in the production of cores for the purpose indicated the core barrel which is usually of metal and consists of a suitable length of a tubular bar or unit is encased manually in 30 a jacket of loose straw, excelsior, paper or like fibrous material of a more or less yielding or springy nature, suitably fastened around the core barrel and provided with a surface coating or scale of mud or wet clay 35 or the like, so that when the core thus constructed is placed in the mold and the metal is poured into the latter around the core, the shrinkage of the metal, which is to form the cast iron pipe and which is necessarily 40 incidental to the cooling of the metal, will be compensated for by the compression of the straw or fibrous jacket to avoid the straining of the casted metal and hence the tend-

ency to produce cracks or fractures therein. Necessarily such a procedure involves 55 a considerable expenditure of time and requires a considerable skill on the part of the laborers upon whom devolves the duty of wrapping or placing the jackets upon the core barrels, with the constant factor of 60 uncertainty as to the regularity with which the jacket is applied and the necessity for smoothing or slicking the mud coating in order to approximate an interior uniformity 65 of the manufactured article.

It is therefore the primary object of the present invention to provide a means for jacketing or scaling the core barrel, in the production of a core, which will permit of the operation being performed mechanically 70 with regularity and without loss of time to the end that greater uniformity in the production of pipes may be secured without involving any increased risk of fracture incident to the contraction of the metal in the 75 cooling or setting thereof.

With these objects in view, the invention consists in a construction, combination and relation of parts of which a preferred embodiment is illustrated in the accompanying 80 drawing wherein:

Figure 1 is a plan view of an apparatus embodying the invention.

Figure 2 is a side view of the same with the removable shield or guard wall partly 85 broken away.

Figure 3 is a longitudinal sectional view showing the movable track elements of the feeding mechanism in their normal or operative relation with the carrier.

Figure 4 is a horizontal section on the plane indicated by line 4—4 of Figure 3.

Figure 5 is a side elevation partly in section upon the plane indicated by line 5—5 of Figure 1.

The machine embodies essentially a carrier adapted for receiving, supporting and ultimately delivering core barrels which during the interval of transportation thereby are subjected to a treatment involving 100 the application to the surfaces of the core barrels of a scale, having the required resilience to permit of the shrinkage of the casted metal and provide a proper interior surface of the product; with which carrier 105 are associated means for depositing the ma-

terial forming the scale upon the exposed surfaces of the core barrels, means for feeding the core barrels to the carrier and including devices adapted for receiving the 5 hot core barrels as they leave the casting pit, means for receiving the completed cores as they are delivered by the carrier, and means for maintaining the material constituting the scale in proper condition to 10 be deposited upon the surfaces of the core barrels.

In the illustrated embodiment of the invention the carrier is of rotary form and includes the transversely spaced disks 10 15 mounted by means of a shaft 11 upon suitable bearing standards 12 and provided with peripheral series of fingers 13 of terminally hook shape spaced to form seats 14 for the respective reception of the terminals of the 20 tubular core barrels 15 which are of a length sufficient to span the interval between the disks or heads of the carrier and which are secured against endwise movement by the 25 guard ring 15' which are shown as attached to the outer surfaces of the series of fingers to close the outer ends of the seats interposed between the same. The fingers are preferably of forked or dual construction 30 consisting of parallel corresponding elements arranged in transverse registration and spaced apart to provide guides for pivotal latches 16 which are mounted in planes between the said finger elements and are preferably pivoted as at 17 for swing- 35 ing movement, each latch preferably serving to close two adjacent seats and thereby lock the terminals of the core barrels against radial displacement during the interval between the charging of the carrier and the 40 delivery of the completed cores.

It is the intention to rotate the carrier at a relatively low rate of speed to provide for the efficient application to the surfaces of the core barrels which are supported 45 thereby of the material forming the scale, as hereinafter explained, and to this end any suitable driving means may be employed in connection with the shaft 11 which for purposes of illustration is provided with 50 a pulley 18 for engagement by a belt 19 suitable for actuation by a motor of either the electric or other type (not shown), and arranged in movable enclosing relation with the carrier is a shield or guard wall 20 55 adapted to be arranged in its operative position during the coating or scaling of the core barrels and to be displaced during the interval of loading and unloading the carrier, and to this end said shield or guard 60 wall is constructed of sections 21 foldably connected as by hinges 22 with the terminal sections of the walls extending at opposite sides of the plane of the carrier adapted 65 to be folded inwardly to occupy positions transverse to the carrier or parallel with the

axis thereof and having fastening means such as a latch 23 for engagement with a catch or keeper 24.

Beneath the carrier or in any preferred convenient relation thereto is arranged a 70 pit 25 designed in the illustrated embodiment of the invention to serve as a reservoir and mixing chamber for the material designed to constitute the jacket or scale with which the core barrels are to be coated in 75 the formation of the cores and preferably provided with agitating means such as the rotary beater 26 having a shaft 27 provided with a terminal pulley 28 which may be actuated by the motor serving to drive the carrier or by any preferred means, and when as indicated the pit is located beneath the carrier it is adapted to receive the overflow or drippings from the carrier as the coating material is applied to the core barrels, 80 said coating consisting of a liquid or fluid mixture of clay, sand, water and a more or less finely ground fibrous material such as excelsior, hay or straw or the equivalent thereof, such mixture being sprayed upon the core barrels by a nozzle 28 connected with a conductor such as a hose 29 including a pumping mechanism 30 and designed to obtain its supply from the pit or mixing chamber.

95

Thus in carrying out the method of producing cores, after the carrier has been loaded with the core barrels the mixture of scaling material is sprayed upon the surfaces of the barrels as the carrier is rotated to 100 progressively present all portions of the surfaces of each core barrel in a common direction or toward the point of discharge of the coating material from the nozzle,—the surplus material which does not at first adhere to the barrels dropping into the pit for remixture and subsequent use, and the scattering or distribution of the material being prevented by the shield or guard wall which is closed around the carrier during the 110 spraying operation.

As the core barrels are usually presented to and taken up by the carrier while in a heated condition soon after leaving the casting pit in which they have served their purpose in the casting of previous pipes, it is obvious that the liquid vehicle of the fibrous and earthy ingredients of the scale will be rapidly evaporated so as to leave the solid materials in the form of a scale or 115 coating on the surface of the core barrels, and by continuing the application of the fluid material during the relatively slow rotation of the carrier, this coating or jacket 120 may be made of any desired thickness to 125 provide for any desired interior diameter of the pipes to be cast around the same as a core, and after a sufficient thickness of the coating or jacket has been deposited the completed cores may be discharged from the car- 130

rier to be subsequently slicked or superficially smoothed (if necessary) and further dried by passing the same through a suitable drying chamber (not shown) preparatory to being conveyed to the casting pit and inserted respectively in the molds in which the pipe sections are to be cast. Such operations of slicking or smoothing and supplemental drying form no part of the present invention and are of relatively negligible importance in view of the fact that the uniform and progressive presentation of the surfaces of the core barrels to the depositing medium through which the plastic or semi-liquid scaling material is applied to the core barrels, serves to insure a comparatively even or uniform distribution of the material upon the surfaces of the core barrels and hence a practically uniform construction and diameter of the cores without resorting to subsequent treatment, which, however, is an indispensable and important feature of the present method of preparing the cores for this purpose.

25 The means for feeding the core barrels to the carrier in the operation of loading the latter embodies a horse 29' consisting of parallel laterally spaced pairs of guide rails 30 between which are arranged the supporting rails 31 mounted on cushioning springs 32 to adapt them to yield as the hot core barrels are thrown thereon on their return from the casting pit, said supporting rails being provided at their outer ends with suitable upstanding stops 33 to prevent the pipes from rolling in the wrong direction and dropping from the horse with the attendant risk of breakage, which is important in view of the relative cost of these core barrels.

35 40 The supporting rails are preferably pivoted at their inner ends as indicated at 34, to the end that the cushioning springs serve to maintain the rails in a downwardly inclined position, serving to feed the core barrels toward the carrier, and in communication with and adapted to receive the core barrels from the horse are the rail elements 35 pivoted as at 36 to permit of their being elevated at their inner ends and thereby removed from operative relation with the carrier after the loading operation of the latter has been completed. These rail elements during the loading operation extend terminally between the planes of the disks 50 or heads forming the side members of the carrier and are provided with terminal stops 37, to prevent the core barrels from rolling from the same at their inner ends, and the pick-up fingers of the carrier overlap or move in intercurrent relation with the inner terminals of the rail elements so as to engage the extremities of the core barrels and by the continued rotation of the carrier roll said core barrels inwardly until they are engaged 60 in the seats provided at the inner ends of

the fingers and are locked by the closing of the latches. The latches in turn are secured in place by transverse locking pins 38 which are subsequently removable by an attendant, as the latches are successively presented at the discharge side of the carrier to permit of the deposit of the completed or jacketed cores upon the delivery rack 39 consisting of parallel rails 40 from which they may be removed by truck or otherwise to be conveyed either directly to the casting pit or intermittently to such supplemental drying means as may be required to insure the necessary solidity of the scale or jacketing material.

70 75 80 The composition of the scale as hereinbefore indicated is such as to afford a substantially yielding quality adapting the same to compression incidental to the contraction of the metal used in casting the product, and as in the present practice the core barrels may be withdrawn from the molds and used repeatedly after the cast metal has been reduced in temperature sufficiently to become set, it being only necessary, as will be understood, to pass said core barrels through the jacketing or scaling machine in order to prepare them for subsequent use.

85 90 95 One of the important features of the structure resides in the fact that the sprayed material employed as the substance for forming the jackets for the cores, is applied from above the surface of the cores supported by a rotary carrier in spaced relation circumferentially of the carrier, so that as the carrier rotates it presents all parts of the surface of each core barrel to the spray or in opposed relation to the movement of the spray, so that a uniform deposit of the jacketing material upon the surfaces of all of the 100 core barrels may be effected. The spray encounters the outer surfaces of the core barrels at the upper side of the carrier and the inner surfaces of the core barrels at the lower side of the carrier, and as the carrier turns 105 those barrels which were at the bottom or lower side of the carrier are gradually turned to the top or under side to present one side and then the other side, progressively so that all portions of the surface of each and every 110 core barrel, are presented in direct opposition to the line of movement of the spray supplied from above the carrier.

115 120 125 130 What is claimed is:

1. A machine for producing cores for use in casting pipes, having a rotary core barrel carrying member and a spraying member for applying fluid scale forming material to the core barrels, said carrying member being continuously movable to progressively and uniformly apply the material to the exterior surfaces of the core barrels.
2. A machine for producing cores for use in casting pipes, having a rotary core barrel carrying member and a spraying member

for applying fluid scale forming material to the core barrels, said carrying member being continuously movable to progressively and uniformly apply the material to the exterior surfaces of the core barrels, the spraying member being located exteriorly of the path of the core barrels.

3. A machine for producing cores for use in the manufacture of cast iron pipes, having a carrier for receiving core barrels and delivering the completed cores, and means for making progressive application of a fluid scale forming material to the core barrels, the carrier being rotary and having an annular series of seats for the reception of the core barrels.

4. A machine for producing cores for use in the manufacture of cast iron pipes, having a carrier for receiving core barrels and delivering the completed cores, and means for making progressive application of a fluid scale forming material to the core barrels, the carrier consisting of parallel rotary disks or heads having seats for the reception of the extremities of the core barrels and pickup fingers for successively engaging and directing the core barrels into said seats.

5. A machine for producing cores for use in the manufacture of cast iron pipes, having a carrier for receiving core barrels and delivering the completed cores, and means for making progressive application of a fluid scale forming material to the core barrels, the carrier consisting of parallel rotary disks or heads having seats for the reception of the extremities of the core barrels and fingers for engaging and directing the core barrels into said seats, in combination with core barrel feeding means having barrel supporting rails to conduct the same to said fingers.

6. A machine for producing cores for use in the manufacture of cast iron pipes, having a rotary carrier for receiving core barrels and delivering the completed cores, and means for making progressive application of a fluid scale forming material to the core barrels, the carrier consisting of parallel disks or heads having peripheral seats for the reception of the extremities of the core barrels and latches for securing the core barrels in said seats.

7. A machine for producing cores for use in the manufacture of cast iron pipes, having a rotary carrier for receiving core barrels and delivering the completed cores, and means for making progressive application of a fluid scale forming material to the core barrels, the carrier consisting of spaced disks having peripheral seats for the reception of the terminals of the core barrels, and pivotal seat spanning latches for locking the core barrels against displacement.

8. A machine for producing cores for use in the manufacture of cast iron pipes, having a carrier for receiving core barrels and de-

livering the completed cores, and means for making progressive application of a fluid scale forming material to the core barrels, the carrier consisting of spaced rotary disks having seats for the reception of the terminals of the core barrels, and pivotal latches for locking the core barrels in said seats, each latch being arranged to close a plurality of seats.

9. A machine for producing cores for use in the manufacture of cast iron pipes, having a rotary carrier for receiving core barrels and delivering the completed cores, and means for making progressive application of a fluid scale forming material to the core barrels, the carrier consisting of terminal spaced disks having peripheral seats for the reception of the terminals of the core barrels, pivotal latches for respectively locking a plurality of the core barrels in said seats, and means for respectively locking the latches in their operative positions.

10. A machine for producing cores for use in the manufacture of cast iron pipes, having a carrier for receiving core barrels and delivering the completed cores, and means for making progressive application of a fluid scale forming material to the core barrels, a foldable shield or guard being arranged in enclosing relation with the carrier.

11. A machine for producing cores for use in the manufacture of cast iron pipes, having a carrier for receiving core barrels and delivering the completed cores, and means for making progressive application of a fluid scale forming material to the core barrels, a foldable shield or guard being arranged in enclosing relation with the carrier and consisting of hingedly connected sections of which the terminal members are adapted for arrangement substantially parallel with the axis of the carrier.

12. A machine for producing cores for use in the manufacture of cast iron pipes, having a carrier for receiving core barrels and delivering completed cores, and means for making progressive application of a fluid scale forming material to the core barrels, the carrier consisting of spaced rotary heads having pick-up fingers for respectively engaging the core barrels, a guard or shield for enclosing the carrier and having terminal sections for arrangement parallel with the axis of the carrier, and a feeding means having pivotally mounted rails for arrangement terminally in intercurrent relation with the pick-up fingers.

13. A machine for producing cores for use in the manufacture of cast iron pipes, having a carrier for receiving core barrels and delivering the completed cores, and means for making progressive application of a fluid scale forming material to the core barrels, the carrier being of rotary construction and having seats for the reception

of the terminals of the core barrels, in combination with core barrel feeding means consisting of a horse having cushioned supporting rails, and connected guide rails for conducting the core barrels to the carrier. 5

14. A machine for producing cores for use in the manufacture of cast iron pipes, having a carrier for receiving core barrels and delivering the completed cores, and means 10 for making progressive application of a fluid scale forming material to the core barrels, the carrier being of rotary construction and having seats for the reception of the terminals of the core barrels, in combination

with core barrel feeding means consisting of 15 a horse having cushioned supporting rails, and connected guide rails for conducting the core barrels to the carrier, said horse having pairs of parallel guide rails between which the cushioned supporting rails are mounted 20 for oscillatory movement.

In testimony whereof, I affix my signature, in the presence of two witnesses.
